No. 895,602.

PATENTED AUG. 11, 1908.

C. P. TRIMBLE.
BED SPRING SUPPORTING FRAME.

APPLICATION FILED SEPT. 16, 1907.

Fig. 1.

UNITED STATES PATENT OFFICE.

CHARLES P. TRIMBLE, OF BELLEVUE, PENNSYLVANIA, ASSIGNOR TO FORT PITT BEDDING COMPANY, OF ALLEGHENY, PENNSYLVANIA, A CORPORATION OF PENNSYLVANIA.

BED-SPRING-SUPPORTING FRAME.

No. 895,602.

Specification of Letters Patent. Patented Aug. 11, 1908.

Application filed September 16, 1907. Serial No. 393,003.

To all whom it may concern:

Be it known that I, CHARLES P. TRIMBLE, a resident of Bellevue, in the county of Allegheny and State of Pennsylvania, have invented a new and useful Improvement in Bed-Spring-Supporting Frames; and I do hereby declare the following to be a full, clear, and exact description thereof.

My invention relates to bed spring supporting frames, and has for its object to provide a frame which can be hung from and used with iron or wooden bed-steeds of varying sizes.

I will now describe my invention so that others skilled in the art may manufacture and use the same, reference being had to the accompanying drawings forming part of this specification, in which

Figure 1 is a plan view showing my invention applied to a frame formed in two sections and in an open position with the spring removed from one section. Fig. 2 is a side elevation of the same in its closed up position. Fig. 3 is a cross-section, showing the manner of application to the rails of a bed-steed. Fig. 4 is a detail perspective view of one of the frame supporting members.

Like symbols of reference indicate like parts in the several figures.

In the drawings, 1 represents the upper frame of the spring and is shown in two sections 2, joined together by the hinges 3 connecting the middle bars 4 of the frame. The rectangular lower or spring-supporting frame 5 is provided with cross-bars 6, and between the frames 4 and 5 are located the helical springs 7, connected at their lower ends to the frame 5 and cross-bars 6, their upper ends being connected to interwoven wires 8 carried by the frame 4. Slidably and pivotally connected to the cross-bars 6 are the hangers or supporting members 9, for connecting the frame 5 to the side rails 10 of the bed, as shown in Fig. 3, and such members are formed of the straps or stirrups 11, which are pivotally mounted on a rod 12 passing through holes 14 in the lips or lugs 13 on said stirrups and through elongated slots 14 in the cross-bars 6 and the end portions of the frame 5. The rod 12 is provided with heads 12' at each end for holding it in place, while centrally of each strap or stirrup is fixed a

hanger 15 which is secured by a rivet 16, the hanger being provided with a hooked end 17.

In Fig. 2 the hangers are shown as being 55 swung around and extending inwardly towards the center of the frame 5, and when the hangers are in this position the spring is ready for packing, storing, or shipping, or may be used in connection with a wooden 60 bed by opening up the sections 2 and resting the cross-bars 6 and side rails 5 of the frame upon the wooden slats of the bed, as the hangers in such position will not interfere 65 with the side rails of the bed.

When the device is to be used in connection with a metal bed, the hangers 15 are swung outwardly to the position shown in Figs. 1 and 3 and their hook-shaped ends 17 engaged with the side rails 10 of the bed. 70

In case of any variance in the sizes of beds as frequently happens with beds of different manufacturers, the hangers 15 may be shifted, such movement being permitted by the slots 14 in the cross-bars 6 and the ends of the 75 frame 5 through which the rod 12 by which the hangers are supported extends.

It will be evident that my improved construction can be used in connection with a single bed-spring frame, and that various 80 modifications and changes may be made in the construction of the device without departing from the spirit of the invention or sacrificing any of its advantages.

I claim:

1. In combination a bed-spring supporting frame provided with slots, stirrups for said frame, a rod passing through said slots and through said stirrups for pivotally and slidably mounting said stirrups, and hangers on 85 said stirrups for engaging with a bed to support said frame.

2. In combination a bed-spring supporting frame provided with elongated slots, a rod passing through said slots, stirrups pivotally 95 mounted on said rod, and hangers on the stirrups for engagement with the side rails of a bed.

In testimony whereof, I, the said CHARLES P. TRIMBLE, have hereunto set my hand.

CHARLES P. TRIMBLE.

Witnesses:

D. C. JENNINGS,
J. N. COOKE.
